UNITED STATES PATENT OFFICE.

RICHARD DE VILLAMIL, OF LONDON, ENGLAND.

STEAM GENERATOR.

Application filed April 24, 1925, Serial No. 25,589, and in Great Britain May 2, 1924.

This invention relates to steam generators and is based on the well known principle or phenomenon that if no, sufficiently large, air-bubbles are present in the water to be boiled the temperature of the same can be raised enormously above the theoretical boiling point, the steam requiring a "nucleus" to start from. The temperature curve thus becoming very flat, the inflow of heat is retarded and this leads to reduced economical efficiency in the boiler or steam generator. Such a condition is found especially in marine boilers, where the condensed steam is continuously passed back into the boiler as feed water, to be there re-evaporated. This unfavourable condition, also, incidentally produces or is liable to produce "priming", as well as overheating and ultimate distortion of the boiler, thus leading to the risk of explosion, water in this state easily becoming a highly explosive material.

The object of the present invention is therefore to provide a simple means of making the temperature curve in the boiler more steep, thus enabling steam to be more rapidly and economically raised. At the same time it will also reduce the tendency to "priming" and explosion to a minimum.

Having regard to such principle, I provide by my invention means for trapping and detaining quantities of steam, in the form of bubbles, adjacent to the heating surface of the generator. Such bubbles being of sufficient size and in adequate number, serve as "nuclei" to effect more rapid, more steady, and therefore more efficient and economical steam production. The character of the boiling is changed from that of a series of very small "explosions" to a rapidly continuous production of steam bubbles. The "frothing" of the water is almost entirely eliminated, such froth, carried over with the steam, being as is well known, one of the chief sources of "priming".

In carrying out my invention the means of trapping the steam may comprise a number of small chambers freely open to the water in the generator, such for instance as a number of metal dome-shaped elements, appropriately cut away at their bases to admit the free passage of water and steam, these elements being suitably spaced apart and connected in series together so as to

form as it were a flexible frame, network, or "mat" which can be conveniently placed at any desired part of the generator, adjacent to the heating surface, and by reason of its flexibility will accommodate itself to the curvature or shape of the part of the generator to which it is applied; it will also admit of being easily passed in or out of the boiler through a manhole.

A suitable method for inter-connecting the elements is to thread them in sections or series more or less loosely on thin wires or rods, suitable "distance pieces" which may take the form of pieces of tubing being interspaced, and then connecting a number of sections by means of cross wires or the like, such connections being such as will preserve the desired flexibility if required.

The particular shape of the steam-trapping elements is immaterial, they can be cylindrical, square, polygonal or other shape so long as they are suitably open below to admit the steam and closed above to entrap same, but the dome shape previously mentioned is a suitable one from the point of view of manufacture.

Embodiments of the invention and methods of application thereof are illustrated in the accompanying drawings in which:—

Fig. 1 is a side elevation showing a number of dome shaped elements interconnected in substantially horizontal relation. Fig. 2 is a plan view of Fig. 1 showing two series of said elements. Figs. 3, 4 and 5 are diagrammatic sections of three different forms of boilers with the device of Figs. 1 and 2 applied thereto, Fig. 6 is a front elevation showing two series of dome-shaped elements interconnected in vertical relation. Fig. 7 is a side elevation of Fig. 6 and Fig. 8 is a diagrammatic section of a type of boiler for which the device of Figs. 6 and 7 is eminently suitable.

To firstly refer to Figs. 1 and 2 of the drawings these show a number of dome-shaped steam trapping elements or chambers *a*, cut away below for example at four points as at *b* to permit free access of water and steam and shown as interconnected by wires *c* as of copper or other suitable material of the desired degree of flexibility passed through holes in the side walls of the elements and spaced apart by interposed

lengths of tubing *d* threaded on the interconnecting wires. The upper parts of the elements must be closed or solid without apertures of any kind to ensure the trapping 5 of the steam and proper production and detention of the bubbles.

A sufficient number of said elements so formed and interconnected are used to build up a frame, network or "mat" of the size 10 required according to the dimensions of the boiler or for so much of same as it is desired to apply the device to, and in the examples illustrated in Figs. 3 to 5 it will be seen that in Fig. 3 in its application to a locomotive 15 boiler *e* such a frame, network or mat *x* is placed upon the flat top of the fire-box *f* in the water space proper; in the single flue marine boiler *g* shown in Fig. 4 the said frame or the like is located in the water 20 space at the top of the flue *h* and by reason of its flexibility will bend to convex shape to conform to the curvature of said flue. Obviously in said Fig. 4 a "mat" can be suitably suspended below the flue *h*. Again in 25 the water tube boiler *i* illustrated in Fig. 5, the framework is placed in the base of the steam drum adjacent to the inlets of the water tubes *j* and also by reason of its flexibility will bend to convex shape to conform 30 to the curvature of said drum.

The form shown in Figs. 6 and 7 is somewhat different to those described and comprises series of the dome-shaped elements *a* in vertical spaced relation, interconnected by 35 wires *c* and spaced by tubular members *d* as before, but said wires *c* and members *d* are located at the sides with two thereof for each element to avoid piercing the upper parts of the elements and to maintain the 40 proper relative positions thereof. Such an arrangement when joined up at its ends will form a kind of apron or "flounce", which is particularly suitable for application to the type of vertical "cross tube" boiler *k* illustrated in Fig. 8 where it is shown as surrounding the sides of the fire box *l*, the method of flexibly connecting the elements permitting it to adapt itself to the contour 45 thereof. The device at the top of the fire box is of the "mat" kind above described. In such application the device would be inserted through the manhole *m* in disconnected state and be positioned, fastened and connected up from within, and if necessary 50 formed of a number of separate sections attachable and connectible also from within in the boiler according to the size of the devices required.

In all the applications illustrated it will 60 be apparent that the elements *a* will entrap and retain quantities of steam in the form of bubbles of such size and number as to serve as the nuclei from which to start and encourage the steam production on the principle previously stated.

The material of the elements need not necessarily be metallic, indeed, earthenware suggests itself as a possibly suitable and cheap material. Even the flexibility of the "mat" (which I consider most advisable 70 for practical reasons) is not an essential part of the idea. One can imagine cases where a certain amount of rigidity might, for structural reasons, be considered as more suitable, special cases requiring special 75 treatment.

What I claim as my invention and desire to secure by Letters Patent of the United States is:—

1. In a steam generator the combination 80 of a heating surface, and means adjacent said surface comprising a plurality of elements freely open below to the water in the boiler and closed above to form traps for the steam bubbles, said elements serving as a nuclei for effecting rapid, steady and efficient steam production, and means for connecting said elements together in the form of a frame network.
2. In a steam generator having a heating 85 surface, means adjacent said surface comprising a plurality of elements freely open below to the water in the boiler and closed above to form traps for the steam bubbles, said element serving as a nuclei for effecting rapid, steady and efficient steam 90 production, and means for connecting said elements together in the form of a frame network, which is flexible to conform to the surface of the generator to which it may be applied.
3. In a steam generator having a heating 95 surface, means adjacent said surface comprising a plurality of elements freely open below to the water in the boiler and closed above to form traps for the steam bubbles, said elements serving as a nuclei for effecting rapid, steady and efficient steam production, and means for connecting said elements together in the form of a frame network, 100 comprising members extending through said elements and tubular distance pieces threaded on said members between the elements.
4. A plurality of hollow elements open 105 at one end for admission of water and closed at the other end to entrap steam bubbles, said elements forming nuclei for effecting rapid, steady and efficient steam production, and means for interconnecting and spacing apart said elements to form a frame-network 110 adapted for insertion in the water space of a steam generator.
5. In combination with a boiler having a 115 water space and a heating surface, a plurality of bubble traps disposed adjacent the heating surface in position to be immersed in the boiler water; said traps being open at their bottoms and closed at their tops; and means for connecting the traps to form 120 a net work, for the purpose specified.

6. In combination with a boiler having a water space and a heating surface, a plurality of dome-shaped bubble traps disposed adjacent the heating surface in position to be immersed in the boiler water; and means for flexibly connecting said traps together in the form of a frame network, said means

comprising flexible members extending through said traps and spacing members on said flexible members between the traps. ¹⁰

In witness whereof I have signed this specification.

R. DE VILLAMIL.
